UNITED STATES PATENT OFFICE.

WILFRED A. HARE, OF DETROIT, MICHIGAN.

FURNACE STOKER.

Application filed November 23, 1922. Serial No. 602,698.

This invention relates to automatic furnace stokers and more particularly to stoking devices especially adapted for use in connection with small heating plants, such as domestic or house heating furnaces and the like.

In applying an automatic stoking device to domestic or small furnaces, difficulty arises due to the limited space within which such a device must be installed in order to make the same universally applicable to furnaces of this character now on the market and an object of the invention is to provide a stoker which may be readily applied to and installed in the several common forms of house heating or domestic furnaces and the like. Further, in the application of an automatic stoker to small furnaces or heating plants, economical operation is essential to commercial success, and therefore, the device should be so constructed as to require only a minimum amount of power for operating the fuel feeding and ash eliminating mechanisms, and it is therefore an object of the present invention to so construct these mechanisms as to secure ease of operation and prevent clogging, whereby a small motor may be employed with assurance of continued and efficient operation. A further object is to provide simple and efficient means for intermittently feeding at regular intervals, measured quantities of fuel to the fire pot or combustion chamber, and means for supplying air to maintain combustion, all combined in a structure adapted to be applied as a unit to a domestic furnace. It is also an object, in such application, to provide a stoking device requiring a minimum of attention and which is simple in construction and efficient in operation, and wherein are embodied other new and useful features, further increasing its reliability and efficiency.

With the above and other ends in view, the invention consists in the matters hereinafter set forth and more particularly pointed out in the appended claims, reference being had to the accompanying drawings in which

Figure 1 is a side elevation of a stoking device illustrative of the invention, with portions broken away and in section to more clearly disclose the construction and showing the device as applied to a furnace structure;

Fig. 2 is a longitudinal vertical section substantially upon the line 2—2 of Fig. 3;

Fig. 3 is a horizontal section, the portion of said figure below the line 2—2 thereof, being a section substantially upon the line

3—3 of Fig. 2 and that portion above said line, being a section substantially upon the line 4—4 of Fig. 2;

Fig. 4 is a sectional detail of the fuel-hopper discharge and measuring mechanism, showing the latter in discharge position to illustrate its operation; and

Fig. 5 is a sectional detail substantially upon the line 5—5 of Fig. 1.

For the purpose of illustrating an application of the invention to a common form of furnace, the lower end portion of a conventional form of furnace is shown, 1 indicating the combustion chamber surrounded by concentric spaced walls 2 forming between them a water space or annular water leg 3, and 4 is the usual ash pit having an entrance opening or doorway 5 in the front side thereof. The casting or plate usually provided for closing the opening 5 to the ash pit may be removed and a front casting or plate 6 substituted therefor or the usual plate when of suitable construction may be employed, said front or plate being provided with an opening to receive a suitable casting 7 forming a section of a suitable fuel delivery trough or passage, such trough section being inserted through the usual draft door opening when the usual furnace front is utilized, and below the opening in the furnace front in which this casting is inserted, is a doorway closed by an ash door 8 (Fig. 2) and through which doorway the ash and cinders may be removed from the ash pit.

Bolted or otherwise secured to the outer end of the casting 7 and to the front plate 6, is a suitable casing indicated as a whole by the numeral 9 and this casing is formed with a continuation of the fuel trough or passage 10 and the outer end of this trough communicates with the fuel measuring device located within the casing and hereinafter described, said measuring device being located to receive fuel from a suitable hopper 11 mounted upon the casing. The casing also forms a housing for driving mechanism for driving a screw conveyor 12 located in and extending longitudinally of the fuel trough 10, said drive mechanism comprising a worm 13 secured upon the armature shaft 14 of an electric motor 15 and engaging a worm wheel 16 which worm wheel is secured upon a shaft 17 which is an extension of the screw conveyor 12, and also a housing for a worm 18 on the shaft 17 and a worm wheel 19 on a shaft 20 extending at right angles to and below the

shaft 17, and further for bevel gears 21 and 22, the gear 21 being secured upon the shaft 20 and the gear 22 upon the end of a shaft 23 which extends through the rear side of 5 the housing parallel with the conveyor screw, and which shaft conveys motion from the shaft 20 for driving underfeed mechanism, hereinafter described, the worm gears 18 and 19 and the bevel gears 21 and 22 being located 10 upon their shafts within a suitable chamber 23' which has an extension or lateral chamber 24 for the worm gears 18 and 19 which chamber communicates with the forward side of the chamber 23' and is 15 closed by a detachable cover plate 25 having a bearing 26 thereon for the forward end of the shaft 17. All of the drive gearing is therefore enclosed within an oil tight chamber in which lubricant may be placed for lubricat- 20 ing these gears.

The fuel conveyor 12 is of the floating screw type, being unsupported within its trough 10 at its inner end and is detachably connected at its outer end to the end of the shaft 17 25 in any suitable manner, as by providing an internally screwthreaded socket 27 on the outer end of the conveyor shaft to be engaged by the screwthreaded end of the shaft 17. The free or unsupported end of this 30 conveyor extends within its trough to a point adjacent the underfeed mechanism to deliver fuel thereto from the measuring device which is located at the outer end of and above the trough 10, and comprises a rotary drum 28 35 having diametrically opposite openings or slots in the sides thereof, one to register with the discharge throat 29 of the hopper 11 in one position of the drum, and the other to register with the inlet to the trough 10 in 40 another position of the drum. This drum is rotatable upon projecting end trunnions 30, upon one of which is secured a segmental gear 31 to mesh with a like segment 32 secured upon a rock shaft 33 which shaft is 45 mounted to rock in bearings on the frame or casing. Motion is imparted to this rock shaft 33 from the shaft 20 below, by means of a crank arm 34 on the shaft 33, to the free end of which arm is pivotally attached a connecting rod 35 having pivotal connection at its 50 lower end with the free end of a crank arm 36 indicated in dotted lines in Fig. 2, on the shaft 20. The drum is thus turned in timed relation to the movements of the other parts, to 55 bring its inlet opening into registry with the hopper throat 29, as shown in Fig. 2, and to bring its discharge opening into registry with the inlet end of the trough 10 as shown in Fig. 4.

60 In order to feed the fuel from the hopper 11 into the throat 29 and prevent clogging, a feed slide 37 is reciprocable across the lower or discharge end of the hopper, in a suitable guide 38, and a flap or plate 39 is pivotally 65 attached at 40 near one edge, to the lower

end portion of the slide, the opposite end of said flap being thickened and rounded as at 41 to rest by gravity and slide upon the top of the measuring drum 28, the reciprocation of the slide and flap carried thereby being so timed relative to the turning movement of the drum, that the flap will be withdrawn from over the opening in the drum as said opening moves into registry with the hopper throat and will be projected over the drum 75 as the same is turned toward discharge position so that clogging of the feed in the throat is prevented by the flap and interference with the cut-off movement of the drum obvi- 80 ated.

To reciprocate the feed slide 37 and flap carried thereby, said slide is provided with a series of teeth 42 to be engaged by a milled gear or segment 43 on the rock shaft 33 and therefore said slide and flap are reciprocated in timed relation to the turning movement of the measuring drum 28. To form a yieldable seat and closure for the lower side of the drum, a shoe or plate 44 having an inner surface curved to conform to the curvature of the outer surface of the drum is provided, and this shoe is pivotally supported at its outer edge, as at 45 to swing upon said pivot into firm contact with the drum and close the discharge outlet from the drum when its inlet opening is in registry with the hopper throat. This shoe is normally held in contact with the drum by means of a weight arm 46 extending outwardly from the pivot 45 of said shoe, and therefore clogging or binding of the drum by reason of particles of fuel getting in between the drum and its closure or seat is prevented, as the shoe may swing away from the drum against the action of its weight-arm and relieve the binding action of any such obstruction, and further, any sifting of fine particles of fuel through the joint or seat is normally prevented as the shoe is firmly held in contact with the drum by the action of the weight arm. The flap or plate 39 reciprocating over the inlet mouth of the drum and across the hopper throat 29, supports the weight of fuel in the hopper and prevents jamming of the fuel in the throat against the drum, thus permitting freer movement of the drum and requiring less power to operate the drum and other fuel feeding members. With this arrangement clogging of any of the fuel feeding mechanism is obviated and efficient operation insured.

110 Ease of operation and consequent minimum power requirements is further insured by the arrangement of the conveyor screw 12 and its driving mechanism in that said screw is continuously driven by the worm 18 and worm gear 19 while measured quantities of fuel are intermittently fed to the screw, and therefore a measured quantity of fuel fed 115 into the trough 10 is quickly conveyed to the 120

underfeed mechanism, hereinafter described, before another charge is delivered to the conveyor, and ease of operation and minimum power requirements are insured as the screw conveyor is never overloaded or buried in fuel and may be rotated at a comparatively high speed.

Reciprocable in suitable ways across the lower or discharge end of the hopper 11 and directly above the feed slide 37, is a manually operable cut-off slide or plate 45* which may be moved in or out by the operator to regulate the discharge of fuel from the hopper onto the feed slide according to the kind and condition of fuel being used.

Bolted or otherwise secured to the inner end of the casting or section 7 which is formed with the major portion of the trough 10 is a casing 46* inclosing the under-feed and its drive mechanism, and also secured to the inner end of the section 7 and to the top of the casing 46*, is an air flue section or casing 47 which is formed with an extension or continuation 48 of the trough 10, said extension leading radially inward to one side of a circular seat 49 for a circular fire pot 50 which extends downwardly within the casing 47 at the axis thereof and has an open lower end and an inner surface which converges downwardly and is formed with a series of steps or ledges 51, each of greater diameter than the one below. This fire pot is arranged to fit loosely within its seat 49 in the casing 47 and is removably supported therein by means of an outwardly extending annular flange 52 on its upper end resting upon the top of said casing.

The mechanism for feeding fuel upwardly into the open lower end of the fire pot which fuel is delivered thereto by the screw conveyor in the trough 10 and its extension 48, comprises a cylinder 53 pivotally supported at its lower end, as indicated at 54 in dotted lines in Fig. 2, in the casing 46* directly beneath the open lower end of the pot, and arranged to swing from the inclined position shown in said figure with its open upper end in position to receive fuel from the inner end of the feed trough, into vertical alignment with said open lower end of the pot. This cylinder is formed with laterally extending wings 55 which are curved concentrically with the axis of pivoted support of said cylinder and the wall 56 of the casing 47, in which wall an opening is formed registering with the open ends of the trough and fire pot, is also curved concentrically with said axis, so that these wings form a closure for said opening in all positions of the cylinder to prevent the escape of fuel into the casing 46* and to support the fuel in the pot when the cylinder is turned out of alignment therewith.

The cylinder 53 is also open at its lower end, but a piston 57 reciprocable therein

forms a closure for this lower end and also a plunger to force the fuel out of the open upper end and upwardly into the fire pot when the cylinder, filled with fuel, is turned to a vertical position.

To swing the feed cylinder upon its pivoted support, the support at one side thereof comprises a shaft 58 (Fig. 1) extending transversely of a lateral extension 59 of the casting 46* and within said extension is a cam member 60 secured upon the shaft 23, said cam being provided with a cam groove 61 engaged by a pin or roller 62 on the end of an arm 63 secured upon the outer end of said shaft 58. The cylinder is thus swung between receiving and discharge positions in timed relation to the feeding of measured quantities of fuel and said cam groove is preferably so formed as to effect a quick swinging movement and a dwell or stationary period at both its receiving (as shown in Fig. 2) and its discharge or vertical position.

The reciprocation of the piston or plunger 57 is also effected in timed relation to the swinging movements of the cylinder and the operation of the feeding mechanism, by providing a second cam groove 64 in the cam member 60 engaged by a roller 65 on the free end of an arm 66 which is secured upon the outer end of a shaft 67 extending parallel with the shaft 58, which shaft 67 is provided with a second arm 68 (Fig. 2) adjacent its inner end extending beneath the open lower end of the cylinder and having its free end pivotally connected to the piston 57 by means of a link or connecting rod 69. The cam groove 64 is preferably so formed as to cause the piston to recede rapidly to the lower end of its stroke after the cylinder has reached its receiving position as shown in Fig. 7, and to remain in that position until said cylinder has been swung to discharge or vertical position when further turning of the cam will effect a slow upward movement of the piston which will gradually force the charge of fuel in the cylinder upwardly into the bottom of the fire pot, pushing the previously fed fuel upwardly in the pot. When the piston has reached the upward or discharge end of its stroke with its upper end face flush with the upper surface of the wings, it is retracted slightly to relieve the pressure of the fuel thereon and is then held in that position during the turning of the cylinder from discharge to receiving position, and as the upper end face of the piston is curved to conform to the curvature of the wings, the fuel is entirely ejected from the cylinder and this end of the piston substantially fills the end of the cylinder, providing a comparatively smooth surface together with said wings, to support the fuel in the fire pot and permit the easy swinging of the cylinder therebeneath, the slight retraction of the piston relieving the

pressure thereon. When the cylinder is in vertical or discharge position, the wing at one side thereof closes the discharge opening from the feed trough and when said cylinder is in position to receive fuel from said opening, the wing at the other side closes the open lower end of the fire pot, and preferably the operation of the measuring drum 28 is so timed relative to the swinging of the cylinder 10 that a measured quantity of fuel will be discharged from the drum into the outer end of the conveyor trough just about the time said cylinder reaches its receiving position so that the charge will be quickly conveyed by the 15 continuously rotating conveyor screw, to the open upper end of the cylinder to fill the same.

As previously described, the fire pot 50 is of inverted truncated conical shape, that is, 20 flared upwardly and outwardly with its bottom opening of smallest diameter and its inner surface formed with the series of steps or ledges 51 so that as the fuel is forced upwardly therein by the piston 57 it will gradually spread out, the bulk resting at its periphery upon the several ledges and bridging across the pot so that the weight of fuel above will be supported by this bridging action of the fuel itself and the gradual upward enlargement of the pot will permit the 30 free upward movement of the fuel therein without clogging.

A series of twyer rings 70 forms an upward extension of the fire pot 50, said rings being 35 superposed loosely, one upon another and the bottom ring being formed with an end rib 71 to fit over an annular rib on the pot and hold said rings in position relative to the pot. Each ring of the series is of greater diameter 40 than the next ring below and the intermediate rings are formed with downwardly extending ribs 72 upon their under sides to rest upon the ring below and form spacers for the rings and also a plurality of radial air passages 45 between the rings for the entrance of air to maintain combustion within the twyer formed by the rings which twyer is an upward extension of the fire pot. Downwardly extending lugs or portions 73 of each rib 72 50 on each ring above the bottom ring, engage over the ring below to center the rings and detachably hold them in place, one upon another, and an annular enclosing wall 74 of a diameter equal to the diameter of the casing 47 below, is bolted or otherwise secured to the top of said casing and is formed with a rounded and inturned upper edge flange 75 extending inwardly and over the upper ring of the series. A series of spaced vertically and inwardly extending ribs 76 is provided upon the inner surface of the wall 74, these ribs also 60 extending inwardly of the flange 75 on the lower side and to the inner edge thereof to engage the upper twyer ring and form air passages opening through the twyer into its

interior or the combustion chamber formed thereby. An annular upwardly extending and outwardly flaring wall member 77 is also secured to the top of the casing 47 with its lower end encircling the supporting flange 52 70 of the fire pot to assist in holding the pot in place and with its upper edge spaced from the upper twyer ring and the wall midway between said rings and the outer wall 74. This wall 77 thus divides the annular space 75 between the wall 74 and twyer and causes the air entering said chamber from the casing 47 through the annular opening 78 in the top of said casing, to pass upwardly around said wall and over the upper edge thereof before it can pass through the air passages formed by the ribs 72 and into the fuel to maintain combustion thereof within the combustion chamber. The ribs 76 in the wall 74 tend to distribute the air flow around the twyer 80 and to direct these air streams into the air ducts between the ribs on the twyer rings, and as the annular wall 77 is spaced from the twyer rings, the air may flow downwardly in the space between it and the lower ring to 90 cool this ring and to supply air to the twyer ducts between this lower ring and the next ring above.

As the fire pot 50 and twyer rings 70 are simply set in place in interlocking relation 95 and firmly secured in position by the enclosing wall 74, the inwardly extending flange 75 of which engages over the upper ring of the series, the entire twyer and fire pot may be quickly and easily removed by simply disconnecting the wall member 74 from the casing 47, when the several parts may be lifted out. Further the construction of the twyer is such that air for maintaining combustion is supplied evenly through the air passages in 100 the twyer at all points of the twyer surrounding the combustion chamber, and as each twyer ring is inclined inwardly and downwardly in cross section, as shown in Fig. 2, the air ducts formed between the ribs 72 will 105 also be inclined inwardly and downwardly toward the combustion chamber so that fuel fed upwardly from the open lower end of the fire pot will not get into and clog these ducts. Further, it will be noted that each succeeding twyer ring is of greater internal diameter 110 than the ring below, thus providing a series of steps or ledges at the inner face of the twyer formed by these rings, which steps or ledges form peripheral supports for the body 115 of fuel which bridges the combustion chamber within the twyer and thus prevents packing and consequent clogging of the fuel in the combustion chamber. The upwardly and outwardly inclined wall formed by the twyer 120 rings also assists in the pushing of the coal upwardly within the combustion chamber from beneath, because of the gradual expansion of the mass within the chamber as it is moved upward and finally flows over the pe- 130

ripheral flange 75 of the enclosing wall 74 of the chamber. The main volume of combustion takes place at the top of the mass of fuel in the combustion chamber but that portion of the fuel which passes over the peripheral edge of the chamber is caught by the annular grate 79 which surrounds the enclosing wall 74 and is burned thereon, combustion being maintained by air from the ash pit 4 which passes upward past the grate through the narrow space between the inner edge of said grate and said wall and between the outer edge of the grate and the surrounding wall 2 of the furnace.

This grate 79 comprises an annular casting having an imperforate upper coal carrying surface which is inclined radially outward and downward and also inclined in the direction of its length, being of spiral formation with the high end and the low end of the spiral surface 80 connected by a vertical portion 81, and, as shown in Fig. 2, this grate is supported upon one or more rolls 82 pivotally mounted upon the outer side of the wall 74 and also by a lever 83 pivoted intermediate its ends, at 84, to the wall of the casing 47 with its upper end loosely engaged between downwardly extending ribs 85 on the grate. To the lower end of this lever 83 is pivotally attached one end of a connecting rod 86, the opposite end being pivotally attached to a disk or wheel 87 secured upon the end of the shaft 23 which serves to transmit motion from the shaft 20 and prime mover or motor 15 for driving the underfeed stocking mechanism previously described. An oscillatory motion is thus imparted to the grate to cause the ash and clinker and residue of coal falling upon the grate over the upper edge of the twyer to travel down the spiral surface of the grate and radially outward toward the surrounding furnace wall 2. The lower end portion of the spiral grate surface is preferably curved downwardly as at 88 to assist the discharge of any large clinker into the ash pit, the finer particles of clinker and the ash being discharged into the ash pit through the narrow space between the outer edge of the grate and the wall 2 during the travel of the residue down the spiral. As the wall 2 presents a smooth surface into contact with which clinker comes during its travel down the incline of the grate, and as the grate surface is also smooth, clogging or binding which would prevent the free movement of the grate, is obviated and unburned portions of coal remain upon the grate until consumed.

To provide air under pressure for maintaining combustion, a fan or blower 89 (Fig. 3) is provided, said fan being secured upon the outer end of the motor shaft 14 to run continuously at the same speed as the motor, and this fan is enclosed within a casing 90 located alongside the casing 9 and supported

thereby and by the front plate 6, said fan casing having an axial air inlet opening 91 and a tangent outlet throat 92 which is connected to the outer end of an air passage 93 formed at one side of the casting 7 parallel with the trough 10 and opens into the casing 47 which surrounds the fire pot and has the annular opening 78 in its top for the upward escape of the air into the chamber enclosed by the wall 74 and surrounding the twyer. A constant supply of air under pressure is thus provided for maintaining combustion within the combustion chamber and by providing an opening 94 in the passage 93 a portion of this air may be passed into the ash pit 80 to maintain combustion upon the grate 79, said opening being provided with a cover or closure 95 for opening or closing the opening to the desired degree so that the amount of air which is permitted to escape into the ash pit may be regulated.

By the described construction, a very compact arrangement is secured embodying all of the elements necessary for efficiently and automatically feeding fuel and maintaining combustion, which construction is particularly applicable to domestic or house furnaces, being a unit construction and of a size and form to be readily inserted in the ash pit of the several forms of furnaces as usually constructed. The construction also insures efficient and uninterrupted operation at a minimum expense due to low power requirements, and as the fuel-feeding mechanism and fan for supplying air to maintain combustion are driven by a single motor mounted upon the casing and directly connected to said mechanism and fan, the proper relative proportion of air and fuel is always maintained. Further, the construction and arrangement is such that the device may be made entirely automatic by providing a thermostatic regulating device (not shown) for stopping and starting the motor so that the fire will be constantly maintained at a rate 100 to maintain the desired house temperature without any attention on the part of the occupant further than to keep fuel in the hopper.

Obviously changes may be made within the scope of the appended claims, in the particular form and arrangement described without departing from the spirit of the invention, and I do not, therefore, limit myself to the construction shown.

Having thus fully described my invention, what I claim is:—

1. In a device of the character described, the combination with a hopper having a discharge throat, a casing beneath said hopper, a measuring device mounted for turning movement in said casing and having an inlet opening to receive fuel from said throat and a discharge opening, a trough member to the outer end of which said casing is attached, 125

said trough member being positioned with its outer end in position to receive fuel discharged from said measuring device, a conveyor in said trough for conveying fuel discharged thereinto by the measuring device, means for operating the conveyor, means for rocking said measuring device about its axis, a plate adapted to project beneath the hopper throat and over the measuring device, and means for operating said plate in timed relation to the rocking movement of said measuring device.

2. In a device of the character described, the combination of a fuel hopper having a discharge throat, a measuring device comprising a drum having an inlet opening to receive fuel from the throat and a discharge opening, a feed slide reciprocable beneath the hopper across said throat, means for reciprocating said slide, means for turning said drum on its axis in timed relation to the reciprocation of said slide, a conveyor beneath the drum to receive fuel charges therefrom, and means for operating said conveyor.

3. A device as characterized in claim 2 and wherein a plate is pivotally connected adjacent one edge to the free end portion of said slide, said plate being free to engage and ride upon the top of said drum adjacent its free edge.

4. A device as characterized in claim 2 and including a manually operable regulating slide for regulating the discharge of fuel from the hopper, said regulating slide being reciprocable across the hopper throat adjacent to and directly above the feed slide.

5. In a device of the character described, the combination of a supporting casing and an extension therefor adapted to be inserted within an opening in a furnace front with the casing projecting outside the furnace, said casing and extension being formed with a passage for fuel to be fed therethrough to the

combustion chamber of the furnace and with an air passage at one side thereof for supplying air to maintain combustion in the combustion chamber, and with an air chamber below the furnace fire pot into which said air passage opens, said air chamber being open at its top to discharge air upwardly around the fire pot, said supporting casing being also formed with a fan chamber communicating with the outer end of said air passage and also forward with a gear chamber, a conveyor in said fuel passage, a fan in said fan chamber, a hopper mounted upon the supporting casing and having a discharge throat communicating with the outer end of said fuel passage, a motor mounted upon said supporting casing, a motor shaft upon which said fan is mounted, and gearing within the gear chamber of the supporting casing for transmitting motion from said motor shaft to operate said conveyor.

6. A device as characterized in claim 5 and including a fuel measuring device mounted in said supporting casing between the outer end of the fuel passage and the hopper throat, and means operated by said gearing for actuating said measuring device.

7. A device as characterized in claim 5 and including a hollow measuring drum mounted in bearings on said supporting casing and having an inlet opening at one side to receive fuel from the hopper throat and a discharge opening at its opposite side for the discharge of measured quantities of fuel into the outer end of said fuel passage, a feed slide reciprocable in ways on the supporting casing across the hopper throat above said measuring drum, and means operated by said gearing for turning said drum on its axis, and reciprocating said feed slide in timed relation to the turning movement of said drum.

In testimony whereof I affix my signature.
WILFRED A. HARE.
